Des. 208,553
Patented Sept. 12, 1967

208,553

ELECTRIC LAMP

Martin M. Siegal, Englewood Cliffs, N.J.
(% Marvel Lamp Co., Fort Lee, N.J. 07024)

Filed Apr. 12, 1966, Ser. No. 1,861

Term of patent 3½ years

(Cl. D26—8)

Fig. 1.

Fig. 3.

Fig. 2.

Fig. 4.

FIGURE 1 is a side elevational view of an electric lamp, showing my new design, the appearance being the same from all sides;

FIGURE 2 is an enlarged fragmentary side elevational view of the globe portion of the lamp, the entire surface thereof having the same general appearance;

FIGURE 3 is a fragmentary cross-sectional view taken on line 3—3 in FIG. 2; and

FIGURE 4 is a fragmentary cross-sectional view taken on line 4—4 in FIG. 2.

I claim:

The ornamental design for an electric lamp, as shown and described.
